UNITED STATES PATENT OFFICE.

JAMES L. MCQUARRIE, OF MONTCLAIR, NEW JERSEY, ASSIGNOR TO WESTERN ELECTRIC COMPANY, OF NEW YORK, N. Y., A CORPORATION OF ILLINOIS.

SELECTOR-SWITCH.

1,122,626.

Specification of Letters Patent. Patented Dec. 29, 1914.

Application filed July 30, 1913. Serial No. 782,070.

To all whom it may concern:

Be it known that I, JAMES L. MCQUARRIE, a citizen of the United States, residing at Montclair, in the county of Essex and State 5 of New Jersey, have invented a certain new and useful Improvement in Selector-Switches, of which the following is a full, clear, concise, and exact description.

This invention relates to a telephone 10 switching apparatus and is particularly designed for use as a line finder although obviously it is adapted to be used for other purposes.

The object of this invention is the provision of a switch by means of which connection between incoming and outgoing lines may be effected with great rapidity and which will positively insure that the moving terminals of one of a pair of lines 20 will be stopped in engagement with the terminals of the other line. In the embodiment of the invention herein disclosed this is accomplished by providing a mechanical stop associated with one of the lines and which 25 is adapted to be placed in the path of the carriage supporting the terminals of the other line, whereby "over-run" is positively prevented.

Referring now to the drawings,— Figure 30 1 represents a face view of the operating mechanism of the device; Fig. 2 is a plan view of the same; Fig. 3 is a sectional view on the line 3—3 of Fig. 1; Fig. 4 is a perspective view of the upper portion of the 35 stop rod showing the operating mechanism therefor; Figs. 5, 6 and 7 are views of the part shown in Fig. 4 showing the stop rod in different operated positions; Fig. 8 is a perspective view showing a pair of stop 40 rods with the stop rings thereon and the rods by means of which these rings are actuated; Figs. 9, 10 and 11 are plan views of one of the structures shown in Fig. 8 with parts broken away showing the rods and 45 rings in different positions; Fig. 12 is a di- agrammatic illustration of the switch and a circuit with which it may be employed.

Referring now to the drawings, each individual switching device briefly described

is as follows: The incoming lines extend to 50 terminals on a panel bank. Mounted parallel to the bank and to each other is a plurality of longitudinally movable shafts or rods 6, each carrying a set or sets of brushes 52 representing outgoing line terminals. Mounted parallel and adjacent to each of the brush shafts is a stop rod 7 carrying a plurality of rotatable stop rings 33 each having a projecting lug 45 adapted to be placed in a position to intersect the 55 path of a stop lug 46 carried on the corresponding brush shaft. Individual to each incoming line is a magnet 50 and a rod 49 actuated thereby, whereby its respective ring 33 on the stop rod of a preselected 60 trunk only would be rotated to stop the brush shaft with the brushes in engagement with the terminals of the proper incoming line.

In a switch such as herein disclosed, the 70 panel would preferably extend vertically and the actuating mechanism would be located either above or below the panel, the brush rod and brushes being located opposite the face of the terminal bank. While only one 75 set of brushes and a portion of one section of terminals are indicated on the drawing, in practice several sets of brushes might be carried by the same brush shaft, each set having access to a separate section of the 80 terminal bank. In this case the brushes would normally be held in retracted or inoperative position by any suitable means and only the set having access to the terminal section in which the calling line terminates would be tripped. This tripping 85 might be controlled by an electromagnet as 69 which could be either common to all the lines terminating in the same section of the panel or individual to each line, as here 90 shown. In a telephone exchange in which this invention is adapted to be used, a plurality of groups of these switching devices would be provided, one switch for each outgoing line, and the corresponding contacts 95 traversed by the brushes of the several switches of a group would represent multiplied terminals of the incoming lines.

Referring now to Fig. 1, 1 and 2 represent supports on which the actuating mechanism of the switch may be mounted. Secured to these supports by means of the brackets 3 is a horizontal member 4 of channel form or any desired construction. Secured at the upper end of the members 1 and 2 is a strip 5 through which extends the brush shaft 6 and the stop rod 7. This strip 10 also forms a support for the actuating means for the stop rod 7. The brush shaft 6 carries at the lower end thereof a flat bar 8 which extends adjacent to the oppositely rotating power drums 9 and 10 fixed to the shafts 11 and 12. These shafts at their opposite ends are rotatably mounted in any suitable manner and are rotatably connected by the gears 13 and 14. The shaft 12 in addition to the gear 14 carries a worm gear 15 engaged by the worm 16 driven from a motor or in any desired manner. Secured to the bar 4 and to a corresponding member 17 is a framework 18 carrying the clutch magnets 19 and 20. The armatures 21 and 22 of these magnets are provided with the upwardly extending portions 23 and 24 carrying the clutch pulleys 25 and 26 respectively. Thus it will be seen that upon energization of one or the other of these magnets, the bar 8 will be clamped between one of the pulleys and a power drum 9 or 10, whereby the shaft will be driven in one direction or the other according to which of the magnets is energized. The bar 8 is provided with openings 27 adapted to be engaged by a pawl 28 pivoted at 31 and which is held in engagement therewith by the spring 29. Upon the energization of the down drive clutch magnet 19, this pawl will 40 be retracted by means of a finger 30 on the projection 23 engaging a pin 32 carried by said pawl. The stop rod 7, at the lower end thereof, extends loosely through the supporting member 4 and is also longitudinally 45 movable. Rotatably mounted on the rod 7 are a plurality of stop rings 33 and spacing sleeves 34, one stop ring being provided for each incoming line. At the upper and lower extremities of the set of rings is a 50 pair of collars 35, 36 connected by the yoke 37, the function for which will hereinafter appear. This yoke and the rings are prevented from longitudinal movement on the shaft by means of the collars 38 and 39 55 fixed thereto. In the upper end of the rod 7 is formed a rack 40 adapted to be engaged by a stepping pawl 41 and a holding pawl 42. The pawl 41 is carried by the armature 43 of the electro-magnet 44. Each of the stop rings 33 is provided with a projecting lug 45 which upon rotation thereof is arranged to be placed in the path of a stop member 46 rigidly secured to the brush shaft 6. Each ring also carries at the opposite 60 side thereof a lug 47 (see Figs. 9 to 11)

adapted to be placed in the line of movement of a projection 48 carried on a longitudinally movable rod 49 when the rod 7 is elevated one step by means of the magnet 44. A rod 49 is provided for each set of terminals in a section of the terminal bank and a ring 33 is provided for each rod. A magnet 50 is provided for each rod 49 for moving it to the left against the tension of a spring 51. The stop rod 7 normally stands 75 so that if any rod 49 be actuated, the projections 48 thereon will pass above the lugs 47 on their respective rings 33. In pre-selected position, however, the rod 7 is elevated one step by means of the magnet 44 80 and pawl 41 so that if a rod 49 is now actuated, one of the projections 48 thereon will engage its co-operating lug 47 and rotate the stop lug 45 into the path of the stop member 46 carried by the brush shaft 6 as shown in Fig. 10. If now the clutch magnet 20 be energized, the brush shaft will be elevated by means of the power drum 10 until the stop member 46 engages the lug 45, when the set of brushes 52 will be brought to rest 85 on the terminals of the proper line as will hereinafter appear. The energization of the magnet 50 need only be momentary as the rings 33 when once rotated remain in their set position until restored to normal by the 90 reset yoke 37. Integral with each collar 35 to which the yoke 37 is secured, is an upwardly projecting finger 53, adapted to be engaged by a projection 54 on a reset rod 55 upon energization of its operating magnet 56. One of these rods 55 and its actuating magnet will be provided for each stop rod 7. Secured to the brush shaft 6, adjacent to the upper end of the stop rod 7, is an arm 57 (see Figs. 4 to 7) which carries a pawl 58 normally held in operative 95 position by a spring 59. Upon return of the brush shaft to its normal position, the pawl 58 will engage a projecting arm 60 on the pawl 42 and as pawls 42 and 41 100 are joined by means of a link 61, both pawls will be retracted, as shown most clearly in Fig. 6, thus releasing the stop rod 7 which will then be returned to normal by gravity 105 or in any desired manner. Secured to the upper end of the rod 7 is a finger 62 which, upon the return of said rod to its normal position, is arranged to engage the pawl 58 and cause it to release the pawls 41 and 42 110 as shown in Fig. 7. Secured to the rod 7, slightly below the member 5, is a collar 63 which limits the upward movement of the rod. In the embodiment of the invention herein disclosed, the terminal bank 106 is 115 located above the stop mechanism and a set of brushes 52 is fixed to the shaft or carriage 6 in a manner to traverse its respective rows of terminals upon longitudinal displacement of the shaft. Secured to the shaft 6 near the upper end thereof is a pair of 120

brushes 81 and 95 arranged to coöperate with the interrupters 82 and 96 for a purpose to be hereinafter described.

Referring now to Fig. 12, I will describe briefly a circuit such as that with which the switch is adapted to be employed. The conductors 64 and 65 represent the conductors of a line to a substation A, and the conductors 66 and 67 represent the conductors of a trunk line. However, it is obvious that this switch is equally well adapted for connecting any incoming and outgoing lines. We will assume that the subscriber at substation A is initiating a call and that the switch here disclosed is arranged to connect the terminals of the conductors 64 and 65 to the terminal brushes 52 of the connecting circuit 66, 67. When the subscriber at A removes his receiver from the hook, a circuit is completed from battery 68, through conductor 64, substation apparatus at A, conductor 65, relays 69 and 70 in series, to ground. Relays 69 and 70 are energized and relay 69 completes a locking circuit for itself through its armature. The energization of relay 70 completes a circuit from battery 71, through relay 72, conductor 73, segment 74 of the allotter interrupter 75, brush 76, conductor 77, magnet 50, conductor 79 and armature of relay 70 to ground. Both relays are energized. The energization of magnet 50 is momentary as the armature of relay 70 immediately falls off. However, it has effected the displacement of its respective rod 49 which by engagement of the projection 48 with the lug 47 of the corresponding ring has rotated a lug 45 into the path of the projection 46 on the brush shaft 6. Relay 72 completes a locking circuit through its right armature and contact, conductor 80, interrupter brush 81 and contacting segment on the interrupter 82 to ground. Through its left armature it completes a circuit from battery 71, through the up-drive clutch magnet 20, whereby the bar 8 is forced into engagement with the power drum 10 and the brush shaft is caused to move upwardly. As the brush shaft 6 moves up, the brush 81 trails over segments and insulated portions of the interrupter 82, but as the relay 72 is made slightly sluggish, it remains energized. When, however, the projection 46 engages the lug 45 of the rotated ring, the shaft will be brought to rest with the brush 81 on one of the insulated portions of the interrupter 82. Relay 72 will now be deenergized and interrupt the circuit for the power magnet 20. The shaft, however, will be held in its elevated position by means of the pawl 28. The energization of the relay 72 also completed a circuit from battery 71 through the left armature and contact of relay 72, brick contact and armature of relay 83, and electro-magnet 44 to ground. This causes the stop

rod 7 to take its final upward step so that the lugs 47 are now positioned above the projection 48 on the rods 49. When the brushes 52 contact with the terminals of the conductors 64 and 65, a circuit will be completed from the central battery (not shown) through conductor 67, right brush and contact, conductor 64, substation apparatus, conductor 65, left brush to relay 84, conductor 66 and back to battery. Relay 84 is energized and completes a circuit from battery through its left armature for relay 85. A circuit is now completed from battery 86, interrupter 87, stepping magnet 88, brush 89, conducting segment 97, conductor 90, left armature and contact of relay 85, and left contact and armature of relay 84 to ground. Magnet 88 is energized and through its armature pawl 91 and ratchet wheel 92 rotates the shaft 93 one step. It may be here noted that the brushes 89, 94 and 76 are all carried by the same shaft 93. A branch from the circuit just traced for the stepping magnet 88 also extends from wire 90, through the brush 95 and conducting segment 96 of the interrupter 82 to ground, the shaft 6 being now in elevated position. We will first assume that the next trunk is idle and ready to be selected. When the brush 89 arrives on the next contact 97, the circuit leading through a conductor corresponding to wire 90 at the next trunk will be opened in both its branches and the shaft 93 will stop. In the meantime the brush 94 will have passed over the contacting segment 98, completing a circuit from battery 99, conductor 100 and relay 83' to ground. The momentary energization of relay 83' will complete a circuit from battery 101 through contact and armature of relay 83', to magnet 44' which is the preselect magnet of the next trunk. The energization of magnet 44' will cause the corresponding stop rod 7' to take one step, as previously described, thus placing the lugs 47 in the path of the projections 48 on the rods 49. If, however, the next trunk had been busy, the circuit through stepping magnet 88 would have been closed at that position through a path corresponding to that previously traced, and the shaft 93 would continue to rotate until brush 89 engaged a contact 97 corresponding to an idle trunk. If a plurality of brush sets are provided, the energization of relay 69 when the subscriber removes his receiver from the hook may be employed to cause the tripping of the brush set having access to the section of the terminal bank in which the calling line terminates. At the end of the conversation, when the calling subscriber at A hangs up his receiver, the relay 84 will be deenergized completing a circuit from battery 102 through relay 103, right armature and contact of relay 85 and contact and

right armature of relay 84 to ground. The energization of relay 103 closes two circuits, one from battery 104 for the return clutch magnet 19, whereby the holding pawl 28 is 5 retracted and the brush carriage is returned to normal position, and one through the reset magnet 56, whereby its corresponding rod 55 is forced to the right, causing the projection 54 thereon to engage the finger 53 of the corresponding reset yoke 37, thus 10 returning the actuated stop ring 33 to its normal position. The apparatus of the used line finder will now be returned to its normal position, while the stop rod 7 of the line 15 finder associated with the next idle trunk will have been elevated to its preselected position.

It is to be understood that the circuits herein described are merely illustrative of 20 the manner in which the switch might be employed.

What I claim is:

1. In a switch, brushes, a carriage for 25 each brush, sets of stationary terminals arranged to be traversed by each of said brushes, mechanical stops respectively individual to said sets of terminals, and operating means common to a plurality of stops for positioning a stop in the path of one of 30 said carriages whereby a brush will be brought to rest on a predetermined set of terminals.

2. In a switch, a plurality of sets of 35 brushes, a carriage for each brush set, a row of stationary terminals arranged to be traversed by each brush, a plurality of mechanical stops individual to each carriage, means for moving said carriages, and operating means common to a plurality of stops for 40 positioning a stop in the path of a carriage, whereby the corresponding brushes will be brought to rest on predetermined terminals.

3. In a switch, a plurality of sets of 45 brushes, a carriage for each set, a row of stationary terminal sets arranged to be traversed by each set of brushes, a plurality of mechanical stops individual to each carriage, actuating devices common to corresponding stops, and means whereby the operation of 50 one of said actuating devices will position a stop in the path of a single one of said carriages at a time.

4. In a switch, a carriage, brushes carried 55 thereby, stationary contacts arranged to be traversed by said brushes, a plurality of rotatable members associated with said carriage, each carrying a stop, and means for rotating one of said members to cause its stop to intercept the path of said carriage.

5. In a switch, a longitudinal movable 60 brush shaft, brushes thereon, sets of stationary terminals arranged to be traversed by said brushes, a mechanical stop for each set of terminals, and means for selectively po-

sitioning said stops in the path of said carriage.

6. In a telephone exchange, longitudinally movable brush shafts, a set of brushes carried by each shaft, rows of stationary terminal sets arranged to be traversed by said sets of brushes respectively, a plurality of mechanical stops for each shaft, said stops being individual to said terminal sets respectively, and means for positioning one of a single plurality of stops in the path of a brush shaft, whereby the brushes carried by said shaft will be caused to stop on the corresponding set of terminals.

7. In a telephone exchange, switch carriages, a set of brushes mounted on each carriage, rows of contact sets arranged to be traversed by said sets of brushes respectively, a plurality of rotatable members associated with each of said carriages, each member having a stop, and means for rotating one of a single plurality of said rotatable members to cause its stop to intercept the path of the corresponding carriage.

8. In a telephone exchange, a circuit, stationary contact terminals therefor, a second circuit, movable brushes in which said second circuit terminates, a carriage for said brushes, a mechanical stop for said carriage, and means actuated upon the establishment of a certain electrical condition in said first mentioned circuit for projecting said stop into the path of said carriage.

9. In a switch, a longitudinally movable brush shaft, a projection carried thereby, a rod adjacent to said shaft, a plurality of relatively movable members carried by said rod, stop lugs carried by each of said movable members, and means for positioning any desired stop lug in the path of said projection.

10. In a switch, a longitudinally movable brush support, a projection carried thereby, a member adjacent to said support, a plurality of rotatable disks on said member, each disk having a lug and means for rotating said disks, whereby said lugs may be positioned in the path of said projection.

11. In a switch, a longitudinally movable brush support, a projection carried thereby, a rod substantially parallel to said support, a plurality of rotatable disks on said rod, each disk having a lug and means for selectively rotating said disks, whereby said lugs may be positioned in the path of said projection.

12. In a telephone exchange, a plurality of longitudinally movable brush shafts, a rod adjacent to each shaft, a plurality of movable stop members on each rod, actuating devices for positioning said stop members in the paths of their respective shafts, said actuating devices being common to corresponding stop members, and means where-

by said actuating devices may be operatively associated with a single plurality of stop members at a time.

13. In a telephone exchange, a plurality of longitudinally movable brush shafts, an adjustable rod adjacent to each shaft, a plurality of movable stop members on each rod, actuating devices common to corresponding stop members whereby they may be positioned in the paths of their respective shafts,

and means for adjusting said rods, whereby said actuating devices may be operatively associated with the stop members of a single rod at a time.

In witness whereof, I hereunto subscribe 15 my name this 26th day of July A. D., 1913.

JAMES L. MCQUARRIE.
